UNITED STATES PATENT OFFICE.

ELMER B. STONE AND STUART W. PARSONS, OF NEW BRITAIN, CONNECTICUT, ASSIGNEES TO THE AMERICAN HARDWARE CORPORATION, OF NEW BRITAIN, CONNECTICUT, A CORPORATION OF CONNECTICUT.

TRUNK LOCK.

Application filed February 6, 1922. Serial No. 534,309.

To all whom it may concern:

Be it known that we, ELMER B. STONE and STUART W. PARSONS, each a citizen of the United States, and a resident of New Britain, in the county of Hartford and State of Connecticut, have invented new and Improved Trunk Locks, of which the following is a specification.

Our invention, while not limited in its nature of use, relates more particularly to the class of devices employed for locking the covers of trunks or similar receptacles to the bodies thereof, and an object of our invention, among others, is to provide a lock 10 for such purposes that shall be extremely durable and particularly efficient for the purposes designed.

One form of device embodying our invention and in the construction and use of which the objects herein set out, as well as others, may be attained, is illustrated in the accompanying drawings, in which—

Figure 1 is a face view of a trunk lock embodying our invention.

Figure 2 is a view in cross section through the same on a plane denoted by the dotted line 2—2 of Figure 1.

Figure 3 is a view in central lengthwise section through the same.

Figure 4 is a detail view in lengthwise section through a fragment of the lock showing its manner of operation.

In the accompanying drawings the numeral 5 indicates a lock plate that is adapted to be secured to a trunk, usually the body thereof, or similar receptacle in any suitable manner, and 6 denotes a catch plate, also adapted to be secured to a trunk, usually the cover, or like receptacle. This

catch plate has a rib 7 stamped up from the metal comprising the plate and extending substantially parallel with the border at a short distance therefrom, providing flanges through which screws, rivets or like fasten-

ings may be extended. This rib is of considerable width and forms a recess 8 on the face of the plate. A catch block 9 is secured to the catch plate within the recess 8 in any suitable manner, this block being of such size that its ends are spaced from the sides of the recess sufficiently to permit a link 10 to be received in such space, said

block having a groove 11 in its upper edge to receive the link for the purpose of securing the edge of the trunk cover to the body. 55

A sealing passage 12 is formed through the block, as particularly shown in Figure 3, to receive a sealing wire 13, that is extended through said passage and around the link 10, the ends of such wire being secured as by a seal 14 in any well known manner common to structures of this class. A hasp receiving groove 15 is formed in that edge of the catch block opposite the groove 11 for the purpose of receiving the edge of a 60 hasp in a manner to be hereinafter described.

An important feature of this invention resides in the manner of securing the block 9 to resist separation of the edge of the trunk body and cover. This block may be secured against the surface of the catch plate by riveting, welding, or other fastening means, and a supporting lip 16 is formed at the edge of the recess 8, and as clearly 70 shown in Figures 3 and 4 of the drawings. The block 9 rests with its lower edge squarely against this lip and thereby a particularly strong and effective means for resisting separation of the body and cover is 75 provided.

A hasp receiving recess 17 is formed at the upper edge of the lock plate 5, extending to and opening out of the edge of said plate, as does also the recess 8 in the catch plate. This recess 17 is formed as by stamping the metal to shape, and it is located between the side parts of a bounding rib 18 extending around the plate substantially parallel with its edge, as does the rib 90 7 on the catch plate. A hole 19 is formed through the plate as by stamping, and a box 20 is secured to the back of the lock plate to close said hole 19 and form a pocket for a lock case 21 secured in any suitable manner to a hasp 22. A flange 23 is formed at the edge of the hole 19, such flange providing a shoulder underneath which locking bolts 24 engage to retain the hasp in its locked position. The mechanism within the 95 lock case may be of any desired construction.

A hasp supporting block 25 is secured in the recess 17 against a hasp supporting lip

26, this supporting lip being similar to the lip 16 on the catch plate hereinbefore described, and to support the block 25 against a force tending to separate the cover from the body. Otherwise the block is secured to the lock plate in any desired manner.

Ears 27 are formed at the end of a flange 28 extending along the edges of the hasp 22, these ears being formed by increasing the width of the flange 28 at this point and by bending a fold 29 of the metal backwardly upon itself to increase the thickness of such ear, and as shown particularly in Figure 2 of the drawings. A pivot 30 extends through the block 25 and through the ears 27 to pivotally attach the hasp to said block, and the link 10 is secured to the ears 27 at a point somewhat removed from the pivot 30, the link being formed from a rod of metal bent into rectangular shape and the free bent ends of such link being extended inwardly through the ears 27.

The ends of the side parts of the hasp are rounded to engage within the rounded groove 15 in the catch block 9, and these rounded ends are so formed with respect to the pivot 30 that cover lifting cams 31 are provided, from which it will be seen, as illustrated in Figure 4, that when the hasp is moved outwardly to disengage it from the lock plate these lifting cams acting within the groove 15 will cause the cover to be forced upwardly to a slight extent. In structures of this class it frequently happens that the cover will stick, and often times considerable force is required to disengage it from the body of the trunk. The cam features just described provides means whereby the cover, under such circumstances, is, in a sense, automatically disengaged, as such disengagement follows the necessity of swinging the hasp outwardly to disengage it from the lock plate.

A sealing tongue 32, shown as broken away in Figure 3 of the drawings, extends from a flange 33 on the lock case 21, this tongue being bent around the lower edge of the flange 28 on the hasp and its free end being extended outwardly between said flange and the end portion of the rib 18, as shown in Figure 3 of the drawings. A sealing wire 34 may be extended through a hole in the tongue 32 and through holes in opposite sides of the rib 18, and a seal 35 may be secured to the wire in any manner common to devices of this class.

We claim:—

1. A lock including a plate, a supporting lip projecting from the edge of said plate in a direction at right angles thereto, and a block mounted on said plate and having its edge located for support by said lip.

2. A lock including a plate having a recess, a supporting lip projecting from the edge of said plate and recess in a direction at right

angles thereto, and a block mounted on the plate within the recess and having its edge located for support by said lip.

3. A lock including a plate stamped to create a bounding rib to form a recess open at one end of the plate, a supporting lip projecting from the edge of said plate and recess in a direction at right angles thereto, and a block mounted on the plate within the recess and having its edges located for support by said lip.

4. A lock including a plate, a supporting block secured to the face of said plate, and a plate hasp pivoted to the block and overlying the block when the plate hasp is in a closed position.

5. A lock including a plate, a supporting block secured to said plate, and a plate hasp movably mounted for engagement with said block to be supported thereby and overlie the block when in a closed position.

6. A lock including a plate stamped to create a bounding rib forming a recess, a supporting block secured to the face of said plate within said recess, a supporting lip projecting in a direction at right angles from the edge of said plate and recess to support said block, and a hasp supported by said block.

7. A lock including a plate, a block secured to the face of said plate and having a sealing passage, and a hasp supported link member mounted for engagement with said block and to be inclosed by a sealing wire extended through said passage.

8. A lock including a supporting plate, means on said plate to pivotally support a hasp, a hasp pivotally supported by said means and having a flange widened at one end to comprise supporting ears, and a pivot extending through said supporting means and said ears.

9. A lock including a plate, a member on said plate to support a hasp, a hasp having a bounding flange widened at its ends to provide folds, one of which appurtenant to each end is turned backwardly against the other to create a thickened ear, and means extending into said ears to secure them to said supporting member.

10. A lock including a plate, a supporting member upon said plate, a hasp having flanges located on opposite sides of said supporting member, each flange at opposite sides of said supporting member being widened and folded over to provide a thickened ear, said supporting member being located between said ears, and means extending through said ears to secure the hasp to said supporting member.

11. A lock including a plate, a supporting member secured to said plate, a hasp having a flange widened at its ends and folded backwardly upon itself to provide thickened ears located on opposite sides of

said supporting member, means extending through said ears and into said supporting members, to pivotally secure them together, and a link pivotally attached to said hasp and supported by said ears.

12. A lock including a plate stamped to create a bounding rib that forms a recess, a lip upturned from the open end of said recess, a hasp supporting member secured to the plate against said lip, a hasp located in said recess and having a flange widened at its opposite ends to provide ears located on opposite sides of said supporting member, means for pivotally attaching said ears to said supporting member, and a link pivotally connected to said hasp and supported by said ears.

13. A lock including a plate stamped to create a bounding stiffening rib, a hasp pivotally mounted on said plate, and a

projection extending from said hasp, said stiffening rib and projection being spaced and having separated openings to receive a sealing wire.

14. A trunk fastener including a plate, a block on the plate, a hasp having side portions pivoted to the block, a catch plate associated with the hasp, the ends of the side portions of the hasp being disposed inwardly of the end of the block when the hasp is in a closed and locked position and the ends of the side portions being of a form to extend beyond the block when the hasp is swung to an open position for engaging the catch plate to force the latter away from the hasp during the opening swinging movement of the hasp.
